United States Patent Office

Des. 198,533
Patented June 30, 1964

198,533

TROWEL

Howard Langlie, Ellsworth B. Nelson, and Albert T. Berg,
Jr., all ½ North Central Plastics, Inc., Ellendale, Minn.

Filed Oct. 28, 1963, Ser. No. 77,176

Term of patent 14 years

(Cl. D35—2)

FIG. 1

FIG. 2

FIG. 3

FIG. 4

FIG. 5

FIG. 6

FIG. 7

FIGURE 1 is a perspective view of a trowel showing our new design;

FIGURE 2 is a top plan view thereof;

FIGURE 3 is a side elevation thereof;

FIGURE 4 is a bottom plan view thereof;

FIGURE 5 is a cross sectional view taken on the line 5-5 of FIGURE 2;

FIGURE 6 is a cross sectional view taken on the line 6-6 of FIGURE 2;

FIGURE 7 is a cross sectional view taken on the line 7-7 of FIGURE 2;

FIGURE 8 is a perspective view of a modified form of the trowel shown in FIGURE 1;

FIGURE 9 is a top plan view thereof;

FIGURE 10 is a side elevation thereof;

FIGURE 11 is a bottom plan view thereof;

FIGURE 12 is a cross sectional view taken on the line 12-12 of FIGURE 9; and

FIGURE 13 is a cross sectional view taken on the line 13-13 of FIGURE 9.

We claim:

The ornamental design for a trowel, as shown and described.
